CLAIM

I claim the ornamental design for a game tile, as shown as described.

DESCRIPTION

FIG. 1 is a perspective view of a game tile according to my new design from a position above the tile looking towards one corner of it;

FIG. 2 is a perspective view looking towards the front of a game tile according to my new design;

FIG. 3 is a right side view of a game tile according to my new design;

FIG. 4 is a top plan view of a game tile according to my new design;

FIG. 5 is a left side view of a game tile according to my new design; and,

FIG. 6 is a perspective view looking towards the rear of a game tile according to my new design.
